UNITED STATES PATENT OFFICE.

S. MORRIS LILLIE, OF PHILADELPHIA, PENNSYLVANIA.

PROCESS OF AND APPARATUS FOR MIXING GLUCOSE WITH CANE-SUGAR.

SPECIFICATION forming part of Letters Patent No. 250,084, dated November 29, 1881.

Application filed April 5, 1881. (No model.)

To all whom it may concern:

Be it known that J. S. MORRIS LILLIE, a citizen of the United States, residing at Philadelphia, in the county of Philadelphia and 5 State of Pennsylvania, have invented a new and useful Process of and Apparatus for Mixing Glucose with Cane-Sugar, of which the following is a specification.

The new article of commerce consists of a mixture of refined cane-sugar and grape-sugar, (dextro-glucose,) in which the latter is present in solution, and not in the granular condition, the proportion of the solution of grape-sugar present in the mixture being such that the latter will be about as moist as the ordinary soft refined sugars. The new article of commerce is, in fact, a soft sugar whose moisture or softness is due to the presence of a sirup of grape-sugar, instead of to the presence of a sirup of cane-sugar, as is the case with the ordinary soft sugars.

My process for the manufacture of this new article of commerce consists in draining more completely than is now done the soft refined sugars of the sirups with which they are mixed as they come from the evaporating-pans, and in charging the sugar thus drained with a quantity of an approximately colorless solution of grape-sugar, or of grape-sugar mixed with other substances sufficient to restore to the sugar the desired degree of moisture or softness.

The process—viz., the more thorough draining the sugars of their contained sirups and the charging them with the grape-sugar solution—may be practiced in a variety of ways, to no particular one of which do I wish to limit myself; but as an example of these ways I will describe the process as it may be carried on 40 in a sugar-refinery, in which the draining of the sugar-magmas is effected in centrifugal draining-machines. The product of such a refinery consists of a series of sugars ranging from a white and superior grade to a comparatively dark and inferior one. The sirups separated from the higher sugars are reboiled and additional percentages of sugar separated, while usually those from one or more of the lower grades are not reboiled, but are sold in 50 the market as sirup.

In treating the higher and whiter grades of sugars for the production of my new article of

commerce, the draining process in the centrifugal machines is continued until the greater part of the sirup ordinarily left in the sugar is separated from it, and then the solution of grape-sugar with which the dried sugar is to be charged is sprayed upon the face of the sugar in the revolving machine and allowed to permeate the mass of the same, the quantity of the 60 solution used being sufficient to restore to the drained sugar the desired degree of moisture. The product resulting is the new article of commerce.

In charging the drained sugar with the grape-sugar solution, as above, care must be taken not to allow any of the grape-sugar solution to pass from the sugar and the machine into the sirup, for grape-sugar possesses the property of preventing cane-sugar from crystallizing 70 from its solutions, and so, if present in a sirup, would lessen the amount of sugar extractable from it by reboiling. This can be done by slackening the speed of the machine during the charging operation, and stopping it before any 75 of the solution begins to flow from it. The charged sugar is removed from the machine thoroughly mixed and then barreled.

In the treatment of the inferior and darker grades of sugar the procedure may be varied 80 from that of the higher grades as follows: The most of the magma-sirup having been separated from the sugar in the machine, the remainder is more or less completely separated from it by washing with a proper washing- 85 liquor, which is sprayed upon the face of the sugar in the revolving machine by means of suitable apparatus, and by which the sugar is purged of the colored magma-sirup and is left comparatively white and pure. After the addition of the washing-liquor the draining is 90 continued until most of it has been removed from the sugar, and then the latter is charged with the solution of grape-sugar and the proper degree of moisture or softness imparted to it, 95 as hereinbefore described.

In the case of those lower-grade sugars the sirups from which are not reboiled, but are sold as sirup, and in which sirups, therefore, the presence of grape-sugar can do no harm, on account of its property of preventing the crystallization of cane-sugar from its solutions, the washing of the sugar to remove the colored sirup may be done with some of the same solu-

tion with which it is to be charged, for any of the solution that might pass into the sirup would be advantageous rather than otherwise, owing to its lighter color, which would lighten 5 that of the sirup and enhance its market value. Such mixtures of cane-sirup and grape-sugar form a common article of commerce, which commands a greater price than the cane-sirup alone.

- 10 In refineries in which the mold system of refining is practiced, the process for the production of my new article of commerce may be carried on as follows: After the purging of the sugar in the molds has been completed, the 15 same is charged with the grape-sugar solution by pouring a proper quantity of the latter upon the surface of the sugar in each of the molds, and allowing it to be absorbed into and permeate its mass.
- 20 The ordinary forms of hard sugar may be made in the usual manner from sugar charged, as above described, with a solution of grape-sugar—that is, by drying the same in ovens, or otherwise, to form hard, dry masses of sugar, 25 and dividing the latter into cut-loaf, crushed, or powdered sugars, as desired; also, the pressed cube-sugar may be made from it in the usual manner.

The solution containing grape-sugar, with 30 which the drained sugars are charged, may be, first, the common white commercial starch-sirup, which is an incrystallizable, or rather a non-granulating, mixture of grape-sugar and dextrine, and which would, therefore, not granulate 35 in the sugar into which it might be charged. It may be, second, a solution of cane-sugar and grape-sugar mixed in such proportions as to form an incrystallizable mixture. It may be, third, a solution of grape- 40 sugar of such a density that when charged into the drained sugar it will dissolve sufficient of the latter to prevent the grape-sugar from granulating—a density of 32° Baumé would answer. Fourth, it may be a solution of any mixture of grape-sugar with other substances, such 45 that the latter will prevent the former from granulating in the charged sugar.

In the drawings I have shown apparatus adapted for carrying on my process for the 50 manufacture of my new article of commerce.

In Figure 1 is shown a centrifugal draining-machine, in combination with apparatus for measuring and spraying the washing or charging liquid upon the sugar in the machine. 55 Figs. 3, 4, 5, and 6 are views of details of the measuring and spraying apparatus. Fig. 2 shows a variation of the measuring device shown in Fig. 1.

In Fig. 1, M is a vertical axial section of an 60 ordinary centrifugal sugar-draining machine charged with sugar.

T is a tube for delivering the washing or charging liquid upon the face of the sugar in the machine, supported in a vertical position 65 by the bracket b, but free to be moved up and down in the same, and extending into the interior of the basket of the machine to an extent

that may be varied by raising or lowering it in the bracket. The face of the tube T toward the periphery of the basket is pierced, as shown 70 in Fig. 6, by a longitudinal slit as long as the basket is deep, and extending from the bottom of the tube upward, so that when the tube is lowered to extend to the bottom of the basket any liquid that may be forced through it will 75 issue from it in a thin vertical sheet, and will be evenly distributed over the face of the sugar in the revolving machine.

On the left of Fig. 1 is shown a device for measuring the liquid as it flows under pressure to the delivery-tube T. It consists of a cylinder, S, containing a closely-fitting piston, whose rod t extends through both heads of the cylinder.

Above the cylinder is a dial, D, having a revolving pointer, p, which is revolved by the motion of the piston through the agency of a slotted cross-head attached to the upper extremity of the piston-rod t, and working with a sliding journal attached to the end of a crank 90 on the arbor of the pointer.

Fig. 4 is a view of the back of the dial-plate D, showing the crank Q on the arbor of the pointer, the sliding journal j, and the slotted cross-head k, attached to the end of the piston-rod t. The motion of the piston and its rod is comparatively slow, and the crank Q is carried over the dead-centers by the action of the bent levers l l' upon a pin (shown in dotted lines) projecting from the crank toward the 100 dial-plate. The levers l l' are pivoted to the back of the dial-plate, near its circumference, one above and one below the center, and on opposite sides of the same. They extend between the crank and the dial-plate, and across 105 the vertical line passing through the center—that is, across the line on which the dead-centers are located. The levers are respectively pressed toward the center by the springs s and s'. As the crank Q is revolved by the piston 110 and approaches a dead-center, the pin on it presses back the lever l, or the lever l', as the case may be, until the crank reaches the dead-center, when the reaction of the lever against the pin will carry it over the line, so that its motion may be continued by the piston. The 115 divisions on the dial all correspond to the same amount of motion of the piston, and, as will hereinafter appear, to the same amount of liquid passed through the cylinder.

In order that greater amounts may be registered than can be done by the dial D, the latter might have in combination with it and operated by it a series of dials, by which would be registered multiples of the total amount 125 registered by the dial D. A familiar example of such a combination of registering-dials is furnished by the ordinary gas-meter.

Communication is had with the interior of the cylinder S by the pipe A through one of its heads, and by the pipe N through the other, the said pipes connecting, respectively, with opposite passages of a four-way cock, C, located below the cylinder. It is shown in transverse

section in Fig. 5. The other two and opposite passages of the cock C connect, respectively, with the pipe E, which communicates with the delivery-tube of the machine M, and with the 5 pipe L, which leads from the supply of the washing or charging liquor. While the plug of the cock is in the position indicated in Fig. 5 the liquor-pipe L will be in communication with the upper portion of the cylinder through 10 the pipe A, and the pipe E will be in communication with the lower portion of the cylinder through the pipe N, and the liquor entering the cylinder through the pipes L and A will exert its pressure upon the upper face of the 15 piston in the cylinder, and any liquor that there may be below the piston will be forced through the tubes E and R, and the delivery-pipe T upon the contents of the basket, supposing the cock c" in the delivery-pipe T to be open. If, 20 after the completion of the downstroke of the piston—the said stroke having been effected by the pressure of the liquor on the upper surface of the piston, as described—the four-way cock C be revolved one-quarter of a revolution, the 25 liquor-pipe L will be put in communication with the pipe N, opening into the lower portion of the cylinder S, and the pipe E will be put in communication with the pipe A, opening into the upper portion of the cylinder, and the pressure of 30 the liquor flowing through the pipe L will be exerted against the under surface of the piston in the said cylinder, and the liquor with which the cylinder above the piston is filled will be forced, through the pipes A and E and the 35 delivery-tube T, upon the contents of the basket of the machine M by the upstroke of the piston, due to the pressure of the liquor against the under surface of the same. If, on the completion of the upstroke of the piston, the four- 40 way cock C be revolved another one-quarter of a revolution, the communications between the various pipes indicated in Fig. 5, and first above set forth, will again exist, the pressure of the liquor from the pipe L will again be upon 45 the upper surface of the piston, and the liquor in the cylinder below the same will be forced into the basket of the machine M. Thus, if, after the termination of each single stroke of the piston, the four-way cock C be revolved 50 one-quarter of a revolution, a discharge of liquor—continuous excepting just at the changes of the strokes, and capable of being made quite continuous by the interposing an air-chamber at some point between the cylinder S and the delivery-pipe T—will be maintained from the delivery-tube T as long as the cock c" in the same is open, and the quantity discharged will be indicated by the motion of 55 the pointer p over the dial D. In the arrangement shown in Fig. 1 this one-quarter revolution of the four-way cock C at the end of each single stroke of the piston is automatically effected by the means and in the manner described in the following:

60 Fitting loosely upon the plug or arbor of the cock C is a lever having two oppositely-radiating arms, z z', and bearing a click, e, which lat-

ter works with a ratchet-wheel, r, firmly keyed to the arbor of the cock C, and having but four teeth, which divide its circumference into 70 quadrants. The arms z z' curve, the former up and the latter down, and extend far enough to the right and to the left, respectively, to be engaged by the lugs d d', projecting from the back of the cross-head a a' at its extremities, as the 75 said cross-head is moved up and down by the piston-rod, to whose end it is attached. Each arm is formed in two parts—viz., u z in the case of one, and u' z' in the case of the other, the former being joined together by the hinge-joint h, and the latter by the hinge-joint h'. The part u of the arm on the right swings upward on the hinge h, and is kept in the closed position, as shown, by gravity, while the part u' of the arm on the left swings downward, 80 and is kept closed by a suitable spring, as indicated in the drawings by the dotted curved line. The weight W suspended from the arm z' tends to move the lever into the position shown, when moved from the same, as herein-after described, but the weight is prevented from revolving it past this position by a suitable stop or check. The operation of this mechanism for automatically turning the arbor of the four-way cock C through one-quarter of a 85 revolution at the termination of each single stroke of the piston is as follows: In the figure the upstroke is supposed to have been completed, the cock C to be in the position shown in Fig. 5, and the downstroke to be about commencing, owing to the pressure of the liquor flowing from the pipe L through the pipe A into the cylinder above the piston. As the piston moves down the lug d on the back of the arm a of the cross-head engages the end 90 of the lever z u, carries it with it, and revolves the lever, which raises the weight W suspended from the other arm of the same. Just before the downstroke is completed the lever will have been revolved so far that the click e, which it 95 bears, will engage the next tooth of the ratchet-wheel r on the arbor of the cock C, and just as the stroke is completed the lug d of the cross-head will pass free of the arm z u of the lever, and the latter will be revolved back into 100 its original position by the weight W, carrying with it the arbor of the cock C through one-quarter of a revolution, thus, as previously described, changing the communications between the various pipes through the four-way cock 105 C, putting the pipe L into communication with the pipe N, and the pipe E with the pipe A, and thus changing the flow of the liquor from the pipe L into the cylinder below the piston, instead of into the same above the piston, 110 and placing the upper portion of the cylinder, which is filled with liquor, into communication with the spraying-tube T of the centrifugal machine, and in consequence of these changes the upstroke of the piston immediately commences, 115 forcing the liquor above the said piston, through the connecting-tubes A and E and the delivery-tube T, upon the sugar in the machine as long as the cock c" in the delivery-tube is 120 125 130

open. During the upstroke the lug d' of the cross-head bears against the under side of the arm $z' u'$ of the lever on the arbor of the cock C, and revolves the said lever in the same direction as in the case of the downstroke, as above described. Shortly before the upstroke of the piston is terminated the click c will engage the next tooth of the ratchet-wheel r, and just as the stroke is ending the lug d' of the cross-head will pass clear of the end of the lever, and the latter will again be revolved into its normal position by the weight W, and the arbor of the cock C will be revolved another one-quarter of a revolution, again making the connections between the various pipes, as indicated in Fig. 5, in virtue of which the piston will again begin its downward stroke, and will force the liquor in the cylinder beneath it (the said piston) through the delivery-tube into the basket of the machine so long as the cock c'' in the tube is open.

The hinged division of the arms of the lever into two parts each permits the arm $z' u'$ on the left to pass the lug d' of the cross-head during the downstroke of the piston, and the arm $z u$ on the right to pass the lug d during the upstroke of the same. The same purpose would be served were the arms of the lever formed each in one piece and the lugs d and d' hinged to the cross-head. The weight W also might be replaced by a suitable spring, tending to keep the lever always in the position shown. Thus it appears that as long as the cock c'' of the delivery-tube T is open and the pressure or head of the liquor in the pipe L is maintained there will be a continuous flow of liquor from the delivery-tube, excepting during the instants at which the changing of the strokes occur, and that the quantity of it discharged through the tube into the basket of the machine will be accurately indicated by the dial D and pointer p.

The liquor-pipe L may have a communication through the cock C' either with the pipe L' , leading to the liquor-supply, or with the hot-water or steam conducting pipe H, the latter connection being to afford means of washing out the apparatus with hot water or steam, as the case may be.

On the side of the cylinder S is a small cock, opening into the interior of the cylinder, just above the piston, when the latter is at the end of its downstroke, and by which the cylinder may be emptied of its contents while the piston is in that position.

The cock C is operated or turned by the weight of the mass W, and the times at which it is turned are determined by the movements of the piston—that is to say, the weight W is lifted, and is allowed to fall and turn the cock at certain times determined by the piston; and it is the principle of the operation of this liquid-meter that at the end of each stroke the piston, acting through proper mechanism, effects a change of communication of the liquor-pipe L, and also of the discharge-pipe E with the cylinder, from one side of the piston to the

other, the said two pipes always communicating with the cylinder on opposite sides of the piston.

The mechanism through which the piston acts may be easily varied from that shown in the drawings, and hereinbefore described, and as an example of such a variation I will point out the following-described mechanism, which is applicable when steam is convenient and the meter large. In this arrangement the four-way cock C is operated by a small steam-cylinder and piston, whose piston-rod connects with a lever of such length, attached to the arbor of the cock, that a stroke of the said steam-piston will turn the arbor of the cock through one-quarter of a revolution, and change the communications between the four ways of the cock, as hereinbefore described.

The valves of the steam-cylinder are worked by the piston of the meter, and in such a manner that at the end of each stroke of the latter the steam-piston will make a stroke, and revolve the arbor of the four-way cock through one-quarter of a revolution in one direction or the other, as the case may be, the effect being that the same changes of communication are made by the cock C and at the same times as in the arrangement shown in the drawings.

In Fig. 2 is illustrated the measuring device arranged, as regards the passage of the piston-rod through the heads of the cylinder, so that any leakage at those points is made impossible. This is done by having the piston-rod projecting through the lower head of the cylinder move in a tube, V, projecting from the bottom of the cylinder, and closed at its lower extremity, and, in a similar manner, having the piston-rod projecting through the top of the cylinder also move in a tube, G, closed at its upper extremity. The latter tube, G, is made of glass, through which the movement of the piston-rod may be noted.

The quantity of liquid passing through the meter is indicated by the motion of the top of the piston-rod with reference to the divisions of the scale J, placed beside the glass tube G. In this arrangement of the measuring apparatus—viz., that shown in Fig. 2—the four-way cock is operated by hand.

Any leakage around the piston from one side of the same to the other, which, should it occur, would vitiate the accuracy of the record on dial of the amount of liquid passing through the meter, may be entirely prevented by having the cylinder S lined with or contain a sleeve made of rubber, prepared cloth, or other suitable pliable integument, the two extremities of which have their edges attached liquid-tight to the walls of the cylinder at its two ends, respectively, while at the middle the sleeve is bound liquid-tight to the circumference of the piston, the latter thus dividing the sleeve into two equal sections contained in the cylinder on opposite sides of the piston. The sleeve is sufficiently long, or is made of sufficiently elastic material, so that either section of it may be extended to the length of the stroke of the

piston, and so, while the sleeve will effectually prevent any flow of liquid from one side of the piston to the other around the same, it will not interfere with the piston and apparatus working in a manner and for the purpose hereinbefore indicated.

Thus, having described the apparatus for carrying on my process for the manufacture of my new article of commerce, I will now describe its operation.

A charge of the sugar-magma is run into the machine, the delivery-tube T having been first raised in its support, and the machine is started. Owing to the centrifugal force due to the revolution of the machine, the sugar-magma flows up onto the walls of the basket, after which the delivery-tube T may be again lowered to the position shown in the drawings, preparatory to spraying the charging-liquor upon the sugar in the revolving machine. The charge of sugar in the machine having been drained as dry as is practicable, the cock c' in the delivery-tube is opened and a quantity of the grape-sugar solution is thrown onto the sugar in the revolving machine, sufficient to impart to the sugar the desired degree of moisture. This having been done, the machine is stopped and the product removed, mixed, and barreled.

In the case of light-colored sugars, the foregoing would be the mode of procedure; but in the case of low dark sugars I prefer to first wash the sugars in the machine with a suitable washing-liquor to remove most of the colored magma-sirup therefrom; and then, after the washing-liquor has been thoroughly drained from the sugar, leaving it comparatively white and dry, to charge the drained sugar with the solution of grape-sugar.

The washing-liquor used in the case of the low dark sugars may be sprayed upon the sugar by the delivery-pipe T , by having the latter have a connection with a supply of the washing-liquor, as well as with the grape-sugar-solution supply, and arranged with suitable cocks, so that it may be put in communication with either; or the machine may be equipped with two delivery-tubes, one for the washing-liquor and the other for the charging-liquid.

I am aware that it is common to mix corn-sirup with cane-sirup for the purpose of forming sirups of a light color, and of a fine general appearance, and also that it has at least been proposed to mix cane-sugar with corn-sirup or starch-sirup; but I am not aware that dry, or comparatively dry, refined cane-sugar has ever been charged with starch-sirup or with a solution of glucose in the proportions indicated in this specification—viz., in such proportions that the product will possess about the same degree of softness or moisture as the ordinary soft sugars of commerce.

Thus, having described my process for producing my new article of manufacture and ap-

paratus for carrying on the same, I claim as mine and desire to secure by Letters Patent of the United States—

1. The within-described process for producing a "soft" refined sugar containing a proportion of grape-sugar in solution, consisting in first more or less completely draining the sugar-magmas, as they come from the evaporating-pans in a refinery, of their contained sirups, and in then charging the resulting drained sugars with a quantity of a solution containing grape-sugar sufficient to impart to the sugars the desired degree of moistness, substantially as specified.

2. The within-described process for producing a soft refined sugar containing a proportion of grape-sugar in solution, consisting, first, in draining, in suitable apparatus, the sugar-magmas, as they come from the evaporating-pans in a refinery, of most of their contained sirups; second, in washing the drained sugars with a suitable washing-liquor to remove from the same the green sirup still remaining in them, and in draining more or less completely from them, also, the washing-liquor; and, third, in charging the drained and washed sugars with the desired amount of a solution containing grape-sugar, substantially as specified.

3. In a delivery-tube projecting into the interior of the basket of a centrifugal draining-machine, and serving to distribute a washing- or other liquid over the contents in the revolving basket, a fine longitudinal slit, as a substitute for the usual perforations for permitting the flow of the liquid from the delivery-tube upon the contents of the basket, substantially as specified.

4. The combination, with the delivery-tube projecting into the basket of a centrifugal draining-machine, and designed for spraying a liquid over the contents of the same, of an apparatus for automatically measuring and recording the quantity of the liquid used as it flows from its source of supply to the delivery-tube, substantially as specified.

5. In a piston liquid-meter, the combination, with the piston and with the induction and eduction pipes of the meter, of the cross-head a a' , the four-way cock C , and the lever on the arbor of the cock, having the two radiating bent and hinged arms z u and z' u' , constructed as described, and held in its normal position by the weight W , or its equivalent, the combination operating at the termination of each stroke of the piston to automatically change the communication of the eduction-pipe, and of the induction-pipe with the cylinder, of the meter, from one side of the piston to the other, substantially as specified.
